DRIVE-BY AND WALK-IN SALES BUILDING

Robert Adler, Dayton, Ohio, assignor to Foto-Fair International Inc., Dayton, Ohio, a corporation of Ohio

Filed Feb. 18, 1969, Ser. No. 15,823

Term of patent 14 years

Int. Cl. D25—04

U.S. Cl. D13—1

FIG-1

FIG-2

FIG-3

FIG-4

FIG-5

FIG-6

FIG-7

FIGURE 1 is a perspective view of a drive-by and walk-in sales building showing my new design, this figure showing the upper portion, the front portion, and the right hand side portion of the building.

FIGURE 2 is a perspective view thereof, showing the upper portion, the rear portion, and the left hand side portion of the building.

FIGURE 3 is a top view thereof.

FIGURE 4 is a front view thereof.

FIGURE 5 is a side view thereof, showing the right hand side portion of the building.

FIGURE 6 is a rear view thereof.

FIGURE 7 is a side view, showing the left hand side portion of the building.

I claim:

The ornamental design for drive-by and walk-in sales building, substantially as shown.
